UNITED STATES PATENT OFFICE.

WILBUR THORPE, OF ST. JOSEPH, MISSOURI.

MECHANICAL KEY-BOARD ATTACHMENT FOR MUSICAL INSTRUMENTS.

SPECIFICATION forming part of Letters Patent No. 281,947, dated July 24, 1883.

Application filed February 7, 1882. (No model.)

To all whom it may concern:

Be it known that I, WILBUR THORPE, a citizen of the United States, residing at St. Joseph, in the county of Buchanan and State of Missouri, have invented certain new and useful Improvements in Mechanical Key-Board Attachments for Musical Instruments; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a front perspective view, showing part of the instrument or organ itself. Fig. 2 gives a rear perspective and partly sectional view, showing the automatic fingering device and the vertical standards that connect them with the keys of the instrument. Fig. 3 is an end view, showing the device for controlling the movement of the roller when adjusted, and for shifting its position after all the tunes contained on the roller have been played. Fig. 4 is a plan view of the roller, showing its journal-bearings. Fig. 5 is a front view of the roller, also showing its journal-bearings and a shifting spring marked P. Fig. 6 is a detached sectional view of the propelling cog-wheel. Fig. 7 is another detached view of the propelling cog-wheel, (with cogs not represented,) simply illustrating the shape of the hole in said wheel. Fig. 8 is a detached view, showing the end of the roller, one end of the mechanical fingering devices, one of the vertical key-standards, and one of the keys of the instrument, said key being marked G.

My invention relates to a mechanical device which is intended to be used in connection with pianos, organs, melodeons, and the like; and it consists in the construction and novel arrangement of parts, as will be hereinafter fully described, and pointed out in the claims appended. This attachment or device is detachably connected in a manner to conveniently take it apart and store away.

The object of my invention is to provide means whereby an organ can be played by any one without the slightest knowledge of music. It is simple in its construction, the music being

produced by a simple and conveniently-operated mechanism.

In the accompanying drawings, forming a part of this specification, similar letters of reference marked thereon indicate like parts of the invention.

In Fig. 1, A is a portion of the instrument. B is a bracket frame-work that supports the gearing of my attachment. C is the roller, provided with angular staples and pointed elevations that raise the mechanical fingers. These elevations are adjusted according to the tune to be produced, so that when the roller is revolved one or more of the elevations will pass under the fingers at a time, and in such systematic order that the keys of the organ will be depressed and released again when the proper note has been measured, as if handled in the old way by the fingers of the operator. These fingers are hinged near their centers to a longitudinal bar marked D, and at right angles to the bar, and said bar is provided with a metal facing, which projects below the under surface of the finger-bar, and this part of the facing is provided with a series of vertical slots the whole length of the finger-bar. These slots serve as guides for the mechanical fingers and admit of their free vertical action, and guide them laterally, so they will always mark the same line around the roller. This insures the fingers against dodging around the note-elevations on the roller when coming in contact with them.

Fig. 2 is in part a rear view of my attachment, showing the connection of the roller with the key-board of the organ, which is as follows: Two horizontal bars are framed into brackets B, which are provided with vertical mortises at intervals corresponding to the keys of the organ. These bars are marked 3 and 4, and in these mortises rest a set of vertical standards, 5 6 7. The feet of these standards rest on the keys of the organ, and their top ends bear against the rear end of the mechanical fingers. Now, when the front end of a finger comes in contact with one of the points or staple elevations on the roller, that end is elevated and the rear end is correspondingly depressed. This pushes the standard under it downward, depressing the key of the organ or instrument, and produces the tone.

The propelling device is a cog-wheel operated by a worm-wheel and crank-shaft. H is the cog-wheel. K is the worm, and L is the crank-shaft. The crank-shaft is mounted in 5 a horizontal position to bracket B, with eye-journal bearings or any suitable journal-box screwed or otherwise fastened to the bracket, the object of this worm device being to impart slow motion to the roller. When the roller 10 revolves, it is necessary for it to move longitudinally to the left, which is provided for by a screw-thread on the journal of the roller, as shown in Figs. 4 and 5. The journal-shaft of the roller projects out beyond its bearing, as 15 shown, and on the part outside of the bearing a thread is cut. Hinged to the bracket, just below this journal, is a caliper-shaped device, (marked O,) the upper ends of which pass through a mortise in lever N. Said lever is 20 made fast to bracket B by one end, as shown, and the other end is left free to move up or down with the hand. When this lever is pressed downward the jaws of the caliper-shaped clamp are moved toward each other, 25 and the inner edge of said jaws have shaved edges to correspond to the channel of the thread, so that when they are forced toward each other these shaved edges bear in the thread on the shaft, and act the same as a stationary threaded nut, so that when the roller 30 revolves this device causes it to move longitudinally to the left. When it is desired to shift the roller again to the right, the operator takes hold of the lever N and raises it, and 35 the points of the device O being crossed, the bearing is reversed and throws them open at the point of contact with the shaft of the roller, and disengages them with the thread, allowing the roller to move freely to the left, said 40 movement to the right being caused automatically by a spring, (marked P,) as shown in Fig. 5. This spring is firmly fastened at its upper end to the bracket B, and bears inward against the end of the roller for that purpose.

45 H is a cog-wheel cast with a sleeve. This sleeve has an angular groove that acts as a journal. Figs. 6 and 7 are both detached views of cog-wheel H, illustrating how it is made. When said cog-wheel is adjusted for work it 50 remains stationary, and the roller-shaft moves longitudinally through it while revolving, being forced to move thus by the thread at the other end. To provide against the shaft of the roller turning in the cog H, there is a channel 55 cut on one side of the bore in the cog, and a corresponding raised rib or flange cast or otherwise made on the shaft of the roller. By this arrangement the hole through the cog can be large enough to admit the shaft through it 60 loosely, and yet prevent the shaft turning the cog on account of the channel and flange or rib. Now, to adjust it to work, the wheel is slipped on the shaft and then let down into the bearing, which bearing straddles over the recessed part of the sleeve of the cog-wheel, and

walls of the annular groove or recess in the sleeve prevent lateral play. Thus the cog is held stationary laterally and can only revolve, and when it is revolved the roller is also forced to revolve. To take the roller out entirely, 70 which is desired sometimes, it is necessary to raise the finger-bar to give room for it to be taken out. This is provided for by two short metal straps, one end of each of which is firmly fastened by screws or otherwise to the end of the 75 finger-bar, and the other end of which is pivoted to the bracket B, so that when bar D is raised it swings upon these pivots. Now, the means for elevating it is found in a pitman-connection, marked N', that is riveted by one 80 end to hand-lever N and by the other to the metal straps N'', as shown in Fig. 3. When the lever N is elevated to disengage clamps O, so that the roller can be taken out or shifted, bar D also is raised out of the way at the same 85 time and by the same operation.

This attachment, when set or attached to an organ or instrument, would cut off free access to the stops. Provisions for the handling these stops is made by providing a lever-connection 90 with them, as shown best in Fig. 3. A strong wire, M, is hinged at R, and has a forked end at bottom, (shown at S in Fig. 3,) which straddles over the stop and closes around it, so that it grips it firmly. The upper end of this wire 95 is elbowed and projects over in easy reach of the operator, so he can handle the stop at will.

Fig. 9 is a detached view of one of the loose journal-bearings. These bearings are held in a groove cut in the upper edge of bracket B, 100 and can be shifted in the groove or slid out at will.

Organs and melodeons having been provided with revolving cylinders or barrels on which airs or tunes are set by pins, and it not being 105 new to automatically play set tunes by simply turning a crank arranged in the case of an instrument and connected by the pin-cylinders, I do not claim either of these devices, broadly.

Having thus fully described my invention, 110 what I claim, and desire to secure by Letters Patent of the United States, is—

1. In a mechanical key-board attachment for musical instruments, the lever N, caliper-shaped clamps O, and shifting-spring P, in 115 combination with bracket B and roller C, substantially as specified.

2. A mechanical key-board attachment for musical instruments, having the elbow-wires 120 M pivoted to the back thereof, substantially as described, whereby the lower ends of said elbow-wires may be attached to the stop-knobs of an organ for operating the same when the device is placed over the key-board, as set forth.

In testimony whereof I affix my signature in 125 presence of two witnesses.

W. THORPE.
